THREAD FORMING CHASER SUPPORTING
AND ADJUSTING MEANS

John S. Bartek, Rochester, N. Y., assignor to Consolidated Machine Tool Corporation, Rochester, N. Y., a corporation of Delaware

Application July 30, 1936, Serial No. 93,438

2 Claims. (Cl. 10—103)

My invention relates to thread forming chaser supporting and adjusting means, with more particular reference to a type of construction which employs a circular chaser, and has for its object 5 to afford a simple and practical arrangement that enables accurate adjustment of the chaser on its supporting block.

A more particular object of the invention is to provide a chaser supporting block adapted to 10 receive a circular chaser, which can be readily positioned therein after grinding, and its operating position determined by a fine adjustment mechanism effective to bring the cutting edge into proper relation to the center line of the 15 machine.

A further purpose of the invention is to afford a construction permitting a fine adjustment of the chaser on its supporting block, and mounting the chaser and adjusting mechanism in such 20 fashion on the block that the helical angle of the thread that is cut is determined by the angular relation of the chaser to the block on which it is mounted.

To these and other ends, the invention consists 25 in the construction and arrangement of parts that will appear clearly from the following description when read in conjunction with the accompanying drawing, the novel features being pointed out in the claims following the specification.

In the drawing:

Fig. 1 is an end elevation of a die head showing the application thereto of one embodiment of the invention;

35 Fig. 2 is a plan view of the same;

Fig. 3 is a side elevation, partially in section, of one of the supporting blocks, and its chaser secured in position;

40 Fig. 4 is a plan view of one of the supporting blocks with the chaser removed;

Fig. 5 is a bottom plan view of the same;

Fig. 6 is an end elevation of the adjusting plate, and

Fig. 7 is an end elevation of the chaser.

45 Referring more particularly to the drawing, in which like reference characters refer to the same parts throughout the several views, 1 designates a die head which may be of conventional form and provided with a series of transverse slots 2 within each of which is mounted a chaser supporting block 3 that abuts the outer face of the head 1 and has a flange 4 engaging and guided in the slot or guideway 2. The several chaser supporting blocks are movable transversely in the 50 slots or guideways 2 for the opening and closing

operations of the die head and are also removable from the die head when different chasers are required, all of which forms no part of the present invention and is in accordance with known types of automatically-opening die head structures. 5

In the present arrangement, each chaser supporting block 3 is provided with a circular type hollow chaser, set at an angle to the longitudinal axis of the supporting block and die head, and the block is provided with means for effecting a 10 fine adjustment of the chaser thereon while maintaining the predetermined angular relation between the chaser and the supporting block.

To accomplish this, the supporting block is provided with a threaded opening 5 disposed at 15 an angle to the longitudinal axis of the supporting block when the latter is positioned in the head, as indicated in Fig. 5, said opening 5 being adapted to receive a clamping screw 6 which acts to hold the chaser on the block. The hollow 20 chaser is designated at 7, having cutting elements arranged parallel, and perpendicular to its longitudinal axis, and the chaser is provided at its front end with a recess to receive the head 8 of the clamping screw. The clamping screw 6 extends through a sleeve 9 that is provided with a series of longitudinally extending serrations arranged exteriorly thereof and which engage corresponding serrations 10 in the interior of the chaser 7 and thus lock the sleeve to the chaser. 30

A portion of the sleeve 9 extends beyond the chaser 7, as shown in Fig. 3, and this part of the serrated sleeve 9 extends within an opening 10a in the adjusting plate 11, the opening in which is similarly serrated to lock the sleeve 9 in relation 35 thereto. The adjusting plate 11 includes oppositely extending arms 12 which underlie the overhanging portion 13 of the supporting block, and said portion 13 is provided with threaded openings 14 that receive the adjusting screws 15. The 40 latter engage the two arms or extensions 12 of the adjusting plate, and are operable to move said adjusting plate in one direction or the other to bring the cutting edge of the chaser in exactly the proper relation to the opposite chaser and to 45 the center line of the machine. The openings 14 which receive the adjusting screws 15 are disposed in a line located at an angle to the outer face of the head and the adjacent face of the supporting block, as shown in Fig. 4, corresponding 50 to the angle at which the chaser is set on the supporting block, so that the adjusting screws will be brought into proper cooperation with the arms 12 on the adjusting plate 11.

With this arrangement, the chaser is provided 55

with cutting elements extending annularly there-around and arranged at right angles to the longitudinal axis of the chaser, the helical angle of the thread being determined by the angular position of the chaser on its supporting block. The chaser is removed from the supporting block for grinding by loosening the clamping screw 8, and after grinding, the chaser and serrated sleeve 9 are positioned within the serrated opening of the adjusting plate 11 so as to bring the cutting edge 16 of the chaser to its approximate proper position, and it is then adjusted accurately to bring its cutting edge in proper relation with the center line of the machine by turning one or the other of the adjusting screws 15. This rocks the sleeve 9 about the clamping screw 8 and with it the chaser until the desired position of the latter is obtained, whereupon the clamping screw 8 is tightened, while the screws 15 act to hold the chaser in its adjusted relation on the supporting block and prevent turning of the same.

While the invention has been described with reference to a particular structural embodiment, it is not confined to the details herein shown, and this application is intended to cover any modifications or departures coming within the purposes of the improvement or the scope of the following claims.

I claim:

30 1. The combination with a support, of a circular chaser, a clamping screw extending through

the chaser and securing it to the support, a sleeve within the chaser surrounding said screw, an adjusting plate surrounding said sleeve and having an oscillatory movement therewith around the screw, the sleeve having exterior serrations engaging corresponding serrations in openings of the same diameter in the chaser and in the adjusting plate for locking said parts together, and means on the support for rocking the adjusting plate about the screw in opposite directions and holding it in adjusted position. 5

2. The combination with a support, of a circular chaser, a clamping screw extending through the chaser for securing it to the support, a sleeve surrounding said clamping screw and provided with exterior serrations engaging corresponding serrations in the chaser, an adjusting plate also surrounding said sleeve and having corresponding serrations engaging therewith whereby the adjusting plate and chaser are locked to the sleeve, 15 the serrated portions of the sleeve within the chaser and adjusting plate being of the same diameter and the adjusting plate having oscillatory movement about the screw for adjustment, oppositely extending arms on said adjusting plate, and 20 adjusting screws threaded in the support and engageable with said arms for rocking the adjusting plate in opposite directions and locking it in adjusted position. 25
